DESIGN FOR A MARKING TABLE

Walter Clifford Cunningham, Horsham, England,
assignor to The National Marking Machine
Company, Cincinnati, Ohio, a corporation of
Ohio

Application January 27, 1947, Serial No. 136,458
In Great Britain August 13, 1946

Term of patent 14 years

(Cl. D33—14)

To all whom it may concern:

Be it known that I, Walter Clifford Cunningham, a subject of the King of England, residing at 43 Kings Road, Horsham, Sussex, England, have invented a new, original, and ornamental Design for Marking Table, of which the following is a specification, reference being had to the accompanying drawings, forming part thereof, in which:

Figure 1 is a perspective view of a marking table, showing my new design.

Figure 2 is a top plan view of my marking table.

Figure 3 is a view thereof in front perspective, and

Figure 4 is a view thereof in rear elevation.

I claim:

The ornamental design for a marking table, as shown.

WALTER CLIFFORD CUNNINGHAM.
